UNITED STATES PATENT OFFICE.

HARRY W. HAMILTON, OF INDIANAPOLIS, INDIANA.

FUEL-FEED SYSTEM.

1,190,757.

Specification of Letters Patent. Patented July 11, 1916.

Application filed February 28, 1916. Serial No. 80,806.

To all whom it may concern:

Be it known that I, HARRY W. HAMILTON, a citizen of the United States, residing at Indianapolis, in the county of Marion and State of Indiana, have invented a new and useful Fuel-Feed System, of which the following is a specification.

In many modern automobiles, the fuel supply tank is placed so low that the feed 10 of the fuel from such tank to the carburetor cannot be obtained by gravity. Therefore, various schemes have been used for feeding gasoline from such a tank to the carburetor.

My invention relates to devices of this 15 kind. Its object is to utilize the vacuum produced in the intake pipe of the engine for obtaining this fuel feed, and to avoid the difficulties which have been encountered with prior constructions, and at the same 20 time to simplify the construction. Among these difficulties may be mentioned the liability of flooding the feed device with fuel on rough roads, when the fuel supply tank is elevated, which flooding has frequently 25 resulted in fires which totally destroyed the automobile; the necessity for lifting the fuel from the main supply tank to the feed device anew at each operation; the loss of 30 vacuum which occurs when the feed device is operated; and the loss of atmospheric pressure on the fuel supply to the carburetor during the suction-action of the feed device.

The accompanying drawing illustrates 35 my invention.

Figure 1 is a diagrammatic view of an automobile equipped with my invention; and Fig. 2 is a vertical central section through the feed device.

In the modern automobile, the engine 10 is usually mounted near the front end of chassis 11, and is provided with an intake manifold 12 which is supplied from a carburetor 13, which is usually near the engine 15

10. In many cases, the fuel supply tank 14 is carried at the rear of the car, and is so low that a gravity feed from it to the carburetor is not possible, the fuel supply tank in many instances being lower than the 15 carburetor when the automobile stands level.

In order to feed the gasoline from the supply tank 14 to the carburetor 13, I provide my improved feed device 20. This feed device in its preferred form comprises a 20 central metal annulus 21, upper and lower glass tubes 22 and 23, and upper and lower

clamping plates 24 and 25, the whole being clamped together by bolts interconnecting the two clamping plates 24 and 25 around the outside of the annulus 21 and the glass tubes 22 and 23. These parts form a unitary chamber 26. This chamber is connected to the fuel bowl of the carburetor 13 by a pipe 27, which enters the chamber 26 through the bottom clamping plate 25 and is provided with a check valve 28 which permits flow of liquid only from the chamber 26 to the carburetor 13 and not in the reverse direction, so that any fuel in the chamber 26 will flow through the carburetor 13 in accordance with the requirements of the latter, and backflow is prevented. The chamber 26 is connected to the intake manifold 12 by a pipe 29, which communicates with the chamber 26 through the upper clamping plate 24, and is provided at its entrance with a valve seat 30 for co-operation with a needle point on the upper end of a needle valve rod 31 having a ball and socket connection 32 to a float 33 located in the lower part of the chamber 26 and connected by a hinge 34 to a downwardly projecting finger 35 from the annulus 21. The valve 30—31 is closed when the fuel level rises in the chamber 26, and is opened when such fuel level falls sufficiently. The chamber 26 is connected to the lower part of the fuel supply tank 14 by a pipe 36; which is provided with a check valve 37 permitting flow of fuel only from the supply tank 14 to the chamber 26 and not in the reverse direction, and communicates with the chamber 26 through a lateral opening 38 in the annulus 21. The communication from the pipe 36 to the chamber 26 is controlled by a valve 39 which is operated by an annular float 40 higher than the float 33, the rod 31 projecting through the float 40. If for any reason the fuel level in the chamber 26 rises above the level required to operate the float 33 to close the valve 30—31, the continued rise of such fuel in the chamber 26 operates the float 40 to close the valve 39, thereby shutting off the supply of fuel to the chamber 26 and preventing flooding. The chamber 26 is also connected to the atmosphere through a pipe 41, which leads to the upper seat of a double acting check valve 42 which has a lateral air inlet opening and a lower valve seat connected by a pipe 43 to the pipe 27 below the check valve 28; the double acting check valve 42 moves up-

ward to prevent ingress of air from the atmosphere to the chamber 26 and permit atmospheric pressure to act on the fuel in the pipe 27 when the vacuum in such chamber 26 rises to a certain point, and moves downward to permit such ingress of air to the chamber 26 and shut off the direct atmospheric connection to the pipe 27 when such higher vacuum does not exist in the chamber 26. The check valve 42 is higher than the highest fuel level in the chamber 26. While I prefer to connect the pipe 43 to the check valve 42, in some instances, I may not do so, but may have the pipe 43 constantly open to the atmosphere at a point higher than the highest fuel level in the chamber 26.

In operation, the engine 10 maintains a partial vacuum in the intake manifold 12. When the fuel in the chamber 26 is below a predetermined level and the valve 30-31 is open, this vacuum is communicated to the chamber 26. This vacuum causes the lifting of the ball 42 to shut off the ingress of air to such chamber and admit it to the pipe 43 and 27, and also causes fuel from the supply tank 14 to flow through the supply pipe 36, check valve 37, float valve 39, and opening 38 into the chamber 26. As the fuel level rises in the chamber 26, it lifts the float 33, and when a predetermined fuel level is reached the float 33 closes the valve 30-31, thus interrupting connection between the chamber 26 and the intake manifold 12, so that as the fuel continues for a moment to flow into the chamber 26 the vacuum in such chamber is lost and the check valve 42 is allowed to drop so as to permit ingress of air from the atmosphere to such chamber and prevent such ingress of air from the atmosphere to the pipe 43. The fuel thus at all times flows to the carburetor as demanded by the engine, flowing by gravity under atmospheric pressure, such atmospheric pressure, on the column of liquid fuel leading to the carburetor always being maintained by the valve 42. As the fuel level falls in the chamber 26, the float 33 does not immediately follow it, but by reason of the vacuum in the pipe 29 remains unpraised until there has been a considerable fall in the fuel level. Then the float 33 drops suddenly to open wide the valve 30-31, thus again connecting the chamber 26 with the intake manifold 12 so as to produce a vacuum in such chamber, causing the ball 42 to rise to shut off the ingress of air and the fuel to flow in again through the pipe 36. If desired, a slight lost motion may be provided in the ball and socket connection 32, so as to permit a longer travel of the float 33 before the valve 30-31 is affected. The foregoing operation is repeated as often as demanded by the engine, a substantially constant gravity fuel supply being maintained from the chamber 26

to the fuel bowl of the carburetor 13. If for any reason the supply tank 14 is elevated, as when the automobile is descending a hill, so that there will be a gravity flow from the supply tank to the chamber 26, with its consequent danger of flooding, this gravity flow is effectually prevented from causing flooding by the float valve 39; for if such gravity flow occurs and raises the fuel level in the chamber 26 after the float 33 has closed the valve 30-31, such rise in fuel level then acts on the float 40 and lifts it to close the valve 39 and stop the flow of fuel, by gravity or otherwise, until the fuel level in the chamber 26 falls. This makes a positive safety device, and effectually prevents the danger of fire from flooding.

The check valve 28 prevents the suction of the engine from drawing fuel from the fuel bowl of the carburetor into the chamber 26. The check valve 37 holds the fuel in the pipe 36 always at the level of the valve 39, so that when the valve 30-31 is opened the fuel is ready in the pipe 36 to enter the chamber 26, and it is not necessary to raise the fuel in the pipe 36. The valve 42, which closes when the valve 30-31 is opened, prevents the loss of vacuum by reason of the leaking in of air.

I claim as my invention:

1. In combination, a liquid chamber having connections to a source of vacuum, to a supply of liquid, and to a device which is to be supplied with such liquid, check valves in said last two connections for preventing flow of liquid from and to said liquid chamber respectively, and float-controlled valves controlled by the liquid level in said chamber for controlling the first and second of said connections respectively, the float-controlled valve controlling said first connection operating at a lower liquid level than the float-controlled valve controlling the second connection.

2. In combination, a liquid chamber having connections to a source of vacuum, to a supply of liquid, and to a device which is to be supplied with such liquid, and float-controlled valves controlled by the liquid level in said chamber for controlling the first and second of said connections respectively, the float-controlled valve controlling said first connection operating at a lower liquid level than the float-controlled valve controlling the second connection.

3. In combination, a liquid chamber having connections to a source of vacuum, to a supply of liquid, and to a device which is to be supplied with such liquid, check valves in said last two connections for preventing flow of liquid from and to said liquid chamber respectively, and float-controlled valves controlled by the liquid level in said chamber for controlling the first and second of said connections respectively.

4. In combination, a liquid chamber having connections to a source of vacuum, to a supply of liquid, and to a device which is to be supplied with such liquid, and float-controlled valves controlled by the liquid level in said chamber for controlling the first and second of said connections respectively. 5
5. In combination, a liquid chamber having connections to a source of vacuum, to a supply of liquid, and to a device which is to be supplied with such liquid, and float-controlled valves controlled by the liquid level in said chamber for controlling the first and second of said connections respectively, both said float-controlled valves closing upon rise and opening upon fall in the liquid level in said liquid chamber. 10
6. In combination, a liquid chamber having connections to a source of vacuum, to a supply of liquid, and to a device which is to be supplied with such liquid, and float-controlled valves controlled by the liquid level in said chamber for controlling the first and second of said connections respectively, the float-controlled valve controlling said first connection operating at a lower liquid level than the float-controlled valve controlling the second connection, both said float-controlled valves closing upon rise and opening upon fall in the liquid level in said liquid chamber. 15
7. In combination, a liquid chamber having connections to a source of vacuum, to a supply of liquid, and to a device which is to be supplied with such liquid, and float-controlled valves controlled by the liquid level in said chamber for controlling the first and second of said connections respectively, said liquid chamber being provided with an air admission opening, and means for closing said air admission opening when the float-controlled valve controlling said first connection is open. 20
8. In combination, a liquid chamber having connections to a source of vacuum, to a supply of liquid, and to a device which is to be supplied with such liquid, a float-controlled valve controlled by the liquid level in said chamber for controlling the first of said connections, and means controlled by the vacuum in the liquid chamber for admitting atmospheric pressure to said third connection independently of the liquid chamber when said float-controlled valve is open. 25
9. In combination, a liquid chamber having connections to a source of vacuum, to a supply of liquid, and to a device which is to be supplied with such liquid, a float-controlled valve controlled by the liquid level in said chamber for controlling the first of said connections, and unitary means controlled by the vacuum in the liquid chamber for admitting atmospheric pressure to said liquid chamber and shutting it off from the third connection save through said chamber when said float-controlled valve is closed and for shutting off atmospheric pressure from said chamber and admitting it to said third connection independently of said chamber when said float-controlled valve is open. 30
10. In combination, an internal combustion engine; a carbureter for supplying explosive mixture to said engine; a fuel supply tank; and a fuel feed device higher than the carbureter and comprising a fuel chamber, separate connections from said fuel chamber to the intake of said engine, to the fuel supply tank, and to the carbureter respectively, check valves in said second and third connections for preventing fuel flow from and to said fuel chamber respectively, and float-controlled valves controlled by the fuel level in said fuel chamber and controlling said first and second connections respectively, the float-controlled valve controlling said first connection being operated at a lower fuel level in said fuel chamber than is the float-controlled valve controlling said second connection. 35
11. In combination, an internal combustion engine; a carbureter for supplying explosive mixture to said engine; a fuel supply tank; and a fuel feed device higher than the carbureter and comprising a fuel chamber, separate connections from said fuel chamber to the intake of said engine, to the fuel supply tank, and to the carbureter respectively, and float-controlled valves controlled by the fuel level in said fuel chamber and controlling said first and second connections respectively, the float-controlled valve controlling said first connection being operated at a lower fuel level in said fuel chamber than is the float-controlled valve controlling said second connection. 40
12. In combination, an internal combustion engine; a carbureter for supplying explosive mixture to said engine; a fuel supply tank; and a fuel feed device higher than the carbureter and comprising a fuel chamber, separate connections from said fuel chamber to the intake of said engine, to the fuel supply tank, and to the carbureter respectively, check valves in said second and third connections for preventing fuel flow from and to said fuel chamber respectively, and float-controlled valves controlled by the fuel level in said fuel chamber and controlling said first and second connections respectively. 45
13. In combination, an internal combustion engine; a carbureter for supplying explosive mixture to said engine; a fuel supply tank; and a fuel feed device higher than the carbureter and comprising a fuel chamber, separate connections from said fuel chamber to the intake of said engine, to the fuel supply tank, and to the carbureter respectively, 50

- and float-controlled valves controlled by the fuel level in said fuel chamber and controlling said first and second connections respectively.
- 5 14. In combination, an internal combustion engine; a carbureter for supplying explosive mixture to said engine; a fuel supply tank; and a fuel feed device higher than the carbureter and comprising a fuel chamber, 10 separate connections from said fuel chamber to the intake of said engine, to the fuel supply tank, and to the carbureter respectively, and float-controlled valves controlled by the fuel level in said fuel chamber and 15 controlling said first and second connections respectively, both said float-controlled valves closing upon rise and opening upon fall in the fuel level in said fuel chamber.
15. In combination, an internal combustion engine; a carbureter for supplying explosive mixture to said engine; a fuel supply tank; and a fuel feed device higher than the carbureter and comprising a fuel chamber, 20 separate connections from said fuel chamber to the intake of said engine, to the fuel supply tank, and to the carbureter respectively, and float-controlled valves controlled by the fuel level in said fuel chamber and controlling said first and second connections respectively, the float-controlled valve controlling said first connection being operated at a lower fuel level in said fuel chamber than is the float-controlled valve controlling said second connection, and both said float-controlled valves closing upon rise and opening upon fall in the fuel level in said fuel chamber.
16. In combination, an internal combustion engine; a carbureter for supplying explosive mixture to said engine; a fuel supply tank; and a fuel feed device higher than the carbureter and comprising a fuel chamber, 25 separate connections from said fuel chamber to the intake of said engine, to the fuel supply tank, and to the carbureter respectively, and float-controlled valves controlled by the fuel level in said fuel chamber and controlling said first and second connections re-
- spectively, said fuel chamber being provided with an air admission opening, and means 50 for closing said air admission opening when the float-controlled valve controlling said first connection is open.
17. In combination, an internal combustion engine; a carbureter for supplying explosive mixture to said engine; a fuel supply tank; and a fuel feed device higher than the carbureter and comprising a fuel chamber, 55 separate connections from said fuel chamber to the intake of said engine, to the fuel supply tank, and to the carbureter respectively, and a float-controlled valve controlled by the fuel level in said fuel chamber and controlling the first of said connections, and means controlled by the vacuum in the fuel 60 chamber for admitting atmospheric pressure to said third connection independently of the liquid chamber when said float-controlled valve is open.
18. In combination, an internal combustion engine; a carbureter for supplying explosive mixture to said engine; a fuel supply tank; and a fuel feed device higher than the carbureter and comprising a fuel chamber, 65 separate connections from said fuel chamber to the intake of said engine, to the fuel supply tank, and to the carbureter respectively, and a float-controlled valve controlled by the fuel level in said fuel chamber and controlling the first of said connections, and 70 means controlled by the vacuum in the fuel chamber for admitting atmospheric pressure to said fuel chamber and shutting it off from the third connection save through said chamber when said float-controlled valve is closed and for shutting off atmospheric pressure from said chamber and admitting it to said third connection independently of said chamber when said float-controlled valve is open.
- 90 In witness whereof, I have hereunto set my hand at Indianapolis, Indiana, this 22d day of February, A. D. one thousand nine hundred and sixteen.

HARRY W. HAMILTON.
